UNITED STATES PATENT OFFICE.

JOHN L. FLANNERY, JR., OF NEW YORK, N. Y.

DESIGN FOR A DISPLAY CARD OR MOUNTING.

51,637.

Specification for Design.

Patented Jan. 1, 1918.

Application filed September 8, 1916. Serial No. 119,127. Term of patent 7 years.

To all whom it may concern:

Be it known that I, JOHN L. FLANNERY, Jr., a citizen of the United States, residing at New York, in the county of New York and State of New York, have invented a new, original, and ornamental Design for a Display Card or Mounting, of which the following is a specification, reference being had to the accompanying drawing, forming a part hereof.

The figure is a plan view of a display card, or mounting, in accordance with my design. The card is of pasteboard, and has the appearance depicted in the drawing.

I claim:

The ornamental design for a display card or mounting, as shown and described.

JOHN L. FLANNERY, JR.
